US00D700394S

(12) **United States Design Patent**
Tang et al.

(10) **Patent No.:** US D700,394 S
(45) **Date of Patent:** ** Feb. 25, 2014

(54) **OPTICAL LENS**

- (71) Applicants: **LedLink Optics, Inc.**, New Taipei (TW); **LedLink Optics (Dong Guan) Co., Ltd.**, Guangdong (CN); **Yang Zhou LedLink Optics Co., Ltd.**, Jiangsu Province (CN)
- (72) Inventors: **Te-Lung Tang**, New Taipei (TW); **Wei-Chiang Huang**, New Taipei (TW); **Chih-Ming Wei**, New Taipei (TW)
- (73) Assignees: **LedLink Optics, Inc.**, New Taipei (TW); **LedLink Optics (Dong Guan) Co., Ltd.**, Guangdong (CN); **Yang Zhou LedLink Optics Co., Ltd.**, Jiangsu Province (CN)

(**) Term: **14 Years**

(21) Appl. No.: **29/439,163**

(22) Filed: **Dec. 7, 2012**

(51) LOC (10) Cl. **26-99**

(52) U.S. Cl.

USPC **D26/124**

(57) **CLAIM**

The ornamental design for an optical lens, as shown and described.

DESCRIPTION

FIG. 1 is a perspective view of a “optical lens” showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is another perspective view thereof.

1 Claim, 5 Drawing Sheets
